(57) **CLAIM**

The ornamental design for a shoe fence, as shown and described.

DESCRIPTION

FIG. 1 is a perspective view of the first embodiment of the design;

FIG. 2 is a front view of the first embodiment of the design;

FIG. 3 is a rear view of the first embodiment of the design;

FIG. 4 is a top view of the first embodiment of the design;

FIG. 5 is a bottom view of the first embodiment of the design;

FIG. 6 is a left side view of the first embodiment of the design, the right side view is a mirror image thereof;

FIG. 7 is a perspective view of the second embodiment of the design;

FIG. 8 is a front view of the second embodiment of the design;

FIG. 9 is a rear view of the second embodiment of the design;

FIG. 10 is a top view of the second embodiment of the design;

FIG. 11 is a bottom view of the second embodiment of the design;

FIG. 12 is a left side view of the second embodiment of the design, the right side view is a mirror image thereof;

FIG. 13 is a perspective view of the third embodiment of the design;

FIG. 14 is a front view of the third embodiment of the design;

FIG. 15 is a rear view of the third embodiment of the design;

FIG. 16 is a top view of the third embodiment of the design;

FIG. 17 is a bottom view of the third embodiment of the design; and,

FIG. 18 is a left side end view of the third embodiment of the design, the right side view is a mirror image thereof.
